US0D1079402S

(12) United States Design Patent (10) Patent No.: US D1,079,402 S
(45) Date of Patent: * Jun. 17, 2025

(54) CUP HOLDER WITH SUCTION CUP

(71) Applicant: Xiaohua Deng, Gaozhou (CN)

(72) Inventor: Xiaohua Deng, Gaozhou (CN)

() Term: 15 Years

(21) Appl. No.: 29/992,518

(22) Filed: Mar. 10, 2025

(51) LOC (15) Cl. 07-09

(52) U.S. Cl.

USPC D7/620

(58) Field of Classification Search

(57) CLAIM

The ornamental design for a cup holder with suction cup, as shown and described.

DESCRIPTION

FIG. 1 is a front, right and top perspective view of a cup holder with suction cup, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the cup holder with suction cup that form no part of the claimed design.

1 Claim, 8 Drawing Sheets
